UNITED STATES PATENT OFFICE.

ETHEL THURSTON TREFFINGER, OF EATON, OHIO.

ATTACHMENT FOR DISHWASHING MACHINES.

Application filed April 11, 1928. Serial No. 269,152.

The primary object of my present invention is the provision of means for converting a motor driven clothes washing machine into a dish washer.

5 A further object is the provision of means for this purpose that shall comprise a mesh body having offset portions at the corner thereof to rest on the top of the tub of a clothes washing machine to support the mesh body therein, said body having an open top and its bottom shaped to correspond with the shape of the upper edges of the agitator blades of the washing machine but, of course, held out of contact therewith, and whereby 10 such blades will force the water through the bottom of the receptacle as well as through the sides thereof for effectively washing dishes which are arranged in the receptacle. In addition to this, the bottom of the receptacle is formed with spaced series of annular upstanding ribs, whose outer walls are inclined towards the sides of the body and whose inner walls are inclined toward the center of the body, and thus afford effective 15 rests and supports for the rims of the dishes that are received therein, while further the body has arranged therein a mesh compartment for the reception of silverware, knives, forks, etc.

20 With the above recited objects in view, the invention further resides in the construction, combination and operative association of parts, such as set forth in the following description, illustrated by the accompanying drawings and specifically pointed out in the appended claim.

In the drawings:

Figure 1 is an approximately central longitudinal sectional view through the tub portion of an electrically driven washing machine having my improvement arranged therein, the latter being also in section.

Figure 2 is a top plan view of my improvement.

45 My invention is especially designed for use in connection with that type of electrically operated washing machines known in the market as the "Maytag". This machine includes a clothes receptacle or tub 1 that has a substantially concaved bottom 2. The bottom, at the center thereof, has upstanding spaced inner and outer tubular sleeves 3 and 4, respectively, there being received centrally through the inner tube 3 the shaft 4' that is turned by the motor. The shaft 4' passes through a bearing that closes the top

of the inner tube and resting on or slightly out of contact with this bearing there is a bushing member whereby the shaft is connected to the outer sleeve 4. The outer sleeve has fixed thereon the hub 5 of the agitating blades 6. The blades are curved both longitudinally and transversely. My improvement comprises a mesh body that is broadly indicated by the numeral 7. In the showing of the drawings, the body is of substantially rectangular formation, the edge at the top thereof being rolled for the reception of a reinforcing wire 8, and this wire 8 is formed with extensions 9 that project angularly through the corners of said mesh body 7. The body 7 is formed with a mesh bottom 10. This bottom is dished inwardly, as at 11, the said dished portion being arranged over but not in contact with the agitator blades 6. The offset elements 9 resting on the top of the tub 1 support the body 7 in the tub and hold the said concaved bottom from contacting engagement with the agitator blades 6.

80 The bottom of the body, at the center thereof, is provided with a round opening that is surrounded by an upstanding tubular portion 12 that surrounds but is out of contact with the outer sleeve 4 of the clothes washing machine, the tubular portion 12 being of a length corresponding the depth of the body.

85 The dished or concaved portion 11 of the body, on the inner face thereof, is formed with spaced annular series of ribs. Each of these ribs defines an outer wall 13 that is directed angularly toward the side of the body and an inner wall 14 which is directed angularly toward the axial center of the 90 body. Thus each of the series of ribs provide gripping elements for engaging the rims of dishes which are inserted therein.

95 The body 7, at one of the corners thereof, is provided with a compartment 15 which is of a finer mesh than that of the body proper and this compartment is designed for the reception of knives, forks, spoons, and other articles to be cleaned by the rotation of the agitator blades 6 of the washing machine.

100 After the dishes have been washed the water may be drawn from the tub of the washing machine and the dishes allowed to stand in the reticulated body 7 until dried or almost dry prior to the wiping thereof. 110 This, of course, is also true with respect to the articles received in the compartment 15.

With my improvement it will be noted that I convert an ordinary clothes washing machine into a dish washer. The construction is extremely simple, cheaply manufactured and easily arranged in or removed from the body or tub 1 of the washing machine.

Having described the invention, I claim:

A means for converting a power driven clothes washing machine into a dish washer, 10 in which the tub of the clothes washing machine is centrally provided with a vertically disposed rotatable shaft, a sleeve surrounding the shaft, a connection between the top of the shaft and the sleeve and said sleeve 15 having fixed thereon a hub having agitator blades, said means comprising a mesh body having an open top, the rim of the body

being rolled, a reinforcing wire in the rim, said wire having angle portions extending therefrom to rest on the top of the tub and 20 to support the mesh body in the tub, the mesh bottom of the body being dished over the agitator blades, and the said dished portion being pressed inwardly to provide the same with spaced series of annular ribs 25 whose outer walls are directed angularly toward the sides of the body and whose inner walls are directed toward the axial center of the body, and said body having a tubular portion extending vertically from the center 30 of its bottom, to surround the sleeve of the machine.

In testimony whereof I affix my signature.

ETHEL THURSTON TREFFINGER.
